SINTERING MACHINE

Reed W. Hyde, Summit, N. J., and Robert D. Pike,
Piedmont, Calif.

Application September 14, 1939, Serial No. 294,810

3 Claims. (Cl. 263—28)

Our invention relates to a sintering machine or furnace of a traveling grate type, burning lime or cement mixtures, in which the material to be burned is carried on a chain of traveling pallets and in which the heat for burning the lime or cement is supplied downwardly from a furnace or combustion chamber positioned above the chain of pallets.

In sintering machines of the above type, the hot products of combustion may be drawn downwardly through the grates of the pallets by suction boxes placed in the pallets and sealed to them. After the burning of the lime or cement is completed, cold air may be blown through the grate to chill the material and this may be done either in a part of the same furnace or in a separate machine.

To obtain uniform burning of the lime and cement and thus to insure that some of the material will not be under burned or over burned, the entrance of air between the edges of the traveling pallets and the furnace wall or the escape of hot products of combustion should be prevented or minimized. This, however, presents the difficulty that the furnace walls and the pallet structure enclosed within the furnace are subjected to the flame or hot products of combustion which are at their maximum temperature within the furnace and before entering or passing into the charge of material on the grate. Sealing material subjected to these temperatures or exposed to radiation, or to contact with the hot gases, would rapidly deteriorate or become ineffective.

Our present invention provides a sealing means between the walls of the furnace and the traveling pallets that is protected from excessive heat or contact with the flame or hot products of combustion.

In our invention the pallets are provided with upstanding side walls which extend to within a short distance of the lower or bottom edge of the side walls of the furnace, being spaced from the side walls just sufficient to insure a clearance between the wall of the furnace and of the pallets at all times.

Preferably, the lower edge or bottom of the furnace wall is inclined upwardly and outwardly for a considerable distance from its inner surface or face and the side walls of the pallets are extended upwardly and outwardly in closely spaced, and preferably parallel, relation to the upwardly and outwardly sloped bottom portion of the furnace wall. In this way the lower part of the furnace wall protects the upward and outward extension of the pallet wall from direct radiation from the interior of the furnace and permits the outward extension to remain relatively cool.

A sealing strip, made either of flexible metal or of heat-resisting material, such as woven or molded asbestos backed with metal, is mounted

on the furnace wall near its outer surface and bears against the wall of the pallet. It may be either on the upper or lower surface of the outward extension and may be held in place respectively by the pressure or suction of the gases within the furnace, or may be held in place by spring pressure.

Preferably, the lower inner edge of the furnace wall extends downwardly somewhat below the normal level of the charge on the pallets or grates and thus also protects the outward extension from direct radiation or from the ready circulation of hot gases.

The side walls of the pallets may be provided with a lining of refractory or heat-resistant material, the inner surface of which may be in appropriate alignment with the inner surface of the furnace wall so that the outer wall portion of the pallets are spaced outwardly and protected from the furnace heat, and may be either vertical or inclined outwardly.

With a vertical wall, the sealing strip attached to the lower part of the furnace preferably bears against the outer surface of the pallet wall and the lower or bottom edge of the furnace wall may be substantially horizontal.

The various features of our invention are illustrated by way of example in the accompanying drawings in which Figs. 1, 2 and 3 are vertical cross-sections through a portion of a furnace wall and pallets embodying various forms or modifications of our invention.

Referring particularly to Fig. 1 of the accompanying drawings, the charge material 10 is supported on grate bars 11 or pallets 12 arranged in a continuous chain and supported by wheels or rollers 13 that run on a track 14. A succession of pallets 12 is provided in such close contact as to form a substantially continuous traveling platform, at one end of which the material 10 to be acted on, such as raw cement mixture or limestone, is supplied and on the other end of which the finished or burned product is delivered.

To supply heat for carrying on the action, which may be endothermic, as in the case of a burned limestone, suitable fuel is burned in a furnace 15 above the charge 10 and the hot products of combustion drawn downwardly therethrough and through the grate bars 11 and pallet structure 12 into a suction box 16 below the chain of pallets. The suction box 16 is sealed to the lower part of the pallets with a suitable seal, such as the flexible strip 17. In passing through the charge 10 heat is absorbed from the hot products of combustion which are accordingly cooled and, therefore, enter the suction box 16 at a much lower temperature. The walls of the furnace 15 are subjected to the high or incandescent temperature of the burning fuel.

The walls of the furnace extend downwardly

a short distance below the level of the top of the charge 10 and a substantial distance above the grates 11. To confine the charge 10 on the grates of the pallet, the pallets are provided 5 with side walls 18 extending upwardly to within a short distance of the lower edge of the furnace wall. They cannot come in direct contact with the lower surface of the furnace wall as that would cause abrasion and destruction of the 10 walls.

To fill in the space between the upper edge of the pallet wall 18 and the lower edge of the furnace wall 15 and provide an effective seal shielded from the high temperatures of the furnace, the lower surface or edge of the furnace wall 15 is inclined upwardly and outwardly as at 15 19 and the pallet wall 18 is provided with an upwardly and outwardly inclined extension 20, the upper surface of which is closely spaced from the 20 surface 19.

The furnace wall 15 may be provided with a supporting structure or ironwork 21, and at the lower edge of this supporting structure there is mounted a sealing strip 22 which may be made 25 of spring metal bearing directly on the upper surface of extension 20, and preferably provided with a facing of flexible refractory material, such as a woven or other form of asbestos sheet, or may consist of a flexible strip of 30 asbestos or other heat-resisting material.

In the event that the furnace 15 is operated under a pressure slightly above atmospheric, the strip 22 might be of easily flexible material held 35 against the surface 20 only by the air or gas pressure.

It will be noted that radiation from the interior of the furnace is cut off from the strip 22 both by the intervening charge 10 and by the fact that there is no direct or straight line path 40 from the strip 22 to the interior of the furnace. The overlapping of the charge 10 and the lower part of the wall 15 also serves to obstruct circulation of gases between the interior of the furnace and the space between the surface 19 45 and the extension 20 and thus provides an insulating or dead air space. Accordingly, the outer part of the extension 20 and the sealing strip 22, which are freely exposed to the outside atmosphere and protected from the heat of the 50 furnace, remain relatively cool.

In the modification shown in Fig. 2, the arrangement of pallets, the charge, the furnace walls and suction box are substantially the same as in Fig. 1. In this modification the lower or 55 bottom edge of the furnace wall is also inclined as at 19 and the pallets are provided with outwardly and upwardly sloping extensions 20, as in the modification of Fig. 1. In this case, however, the sealing strip 22 is arranged to bear 60 against the under inclined surface of the extension 20 and to provide the proper spacing there is a spacing block 23 between the strip 22 and the supporting structure 21 of the furnace wall. This has the advantage, when the furnace 65 is under reduced or sub-atmospheric pressure, of tending to draw the strip 22 into close flexible engagement with the surface of the extension 20.

In the modification shown in Fig. 3, the arrangement and relative position of the pallets 70 12, furnace wall 13 and suction box 16 is similar to that of Figs. 1 and 2. But the charge 10 need

not come above the lower edge of the furnace wall 15. In this case, the side wall 18 extends directly upwardly to a very short space or distance below the lower edge or bottom of the furnace wall 13 and is protected by a refractory liner 24, the inner surface of which slopes to approximate alignment with the wall 13 and which is of approximately the same height as the depth of the charge 10; consequently the wall 18 is protected or insulated from the full heat 10 of the furnace gases and of the charge 10, and being exposed to the outside atmosphere is 15 relatively cool.

Moreover, it is spaced outwardly from the interior of the furnace wall and protected by the portion of the wall 13 immediately above the liner 24. The space between the upper edge of the wall 18 and the lower edge or bottom of the wall 13 is closed by means of a flexible sealing strip 25 which is secured to the lower horizontal 20 edge or bottom of the wall 13 and is bent or flexed to about 90° into a position to lie against the outer vertical surface of the wall 18. The flexing of the strip 25 serves to hold it against and seal the wall 18, this action being aided by 25 the suction within the furnace when the latter is run under sub-atmospheric pressure.

Through the above invention a sealing means is provided through a series of travelling pallets and the walls of the furnace positioned there- 30 above and is protected against the hot gases and the radiant heat from within the furnace. The resiliency of the seal may thus be preserved and distorting, due to changes in temperature, 35 avoided.

What we claim is:

1. A sintering apparatus comprising a chain of travelling pallets, the combination of a furnace having a wall extending vertically upward from the edge of said chain of pallets, each pallet 40 of said chain having a wall extending upwardly from the edge of said pallet below the lower edge of the inner surface of said furnace wall and thence inclined outwardly and upwardly, the bottom of said furnace wall being inclined substantially parallel with said inclined extension, and a sealing strip mounted on said wall beyond 45 said inclined extension and extending inwardly thereof and flexibly sealing against a surface of said inclined extension.

2. A sintering apparatus comprising a chain of traveling pallets, the combination of a furnace having a wall extending vertically upward from the edge of said chain of pallets, each pallet of said chain having a wall extending upwardly from the edge of said pallet below the lower edge of the inner surface of said furnace wall and thence inclined outwardly and upwardly, the bottom of said furnace wall being inclined substantially parallel with said inclined extension, and a sealing strip mounted on said wall beyond 55 said inclined extension and extending inwardly thereof and flexibly sealing the upper surface of said inclined extension.

3. The apparatus of claim 1 in which said sealing strip has a yieldable resilient surface 60 resistant to heat bearing against the surface of said pallet.

REED W. HYDE,
ROBERT D. PIKE. 70
